(Cl. D3—11)

FIG. 1

To all whom it may concern:

Be it known that we, Helen H. Kumme and Madeleine B. Sunkees, citizens of the United States, residing, respectively, in Pelham, New York, and Los Angeles, California, have invented a new, original, and ornamental Design for a Glove or Similar Article, of which the following is a specification, reference being had to the accompanying drawing, forming a part thereof.

In the drawing:

Fig. 1 is a rear view of a glove, showing our new design; and

Fig. 2 is a side elevation thereof.

The essential features of our design reside in the portions shown in solid lines on the drawing.

We claim:

The ornamental design for a glove or similar article, as shown and described.
